UNITED STATES PATENT OFFICE.

HERMANN ALBRECHT, OF PHILADELPHIA, PENNSYLVANIA, ASSIGNOR TO
THE AMERICAN MACHINE COMPANY, OF SAME PLACE.

ICE-CHIPPING TOOL.

SPECIFICATION forming part of Letters Patent No. 296,501, dated April 8, 1884.

Application filed February 6, 1884. (No model.)

To all whom it may concern:

Be it known that I, HERMANN ALBRECHT, a citizen of the United States, and a resident of Philadelphia, Pennsylvania, have invented 5 certain Improvements in Ice-Chipping Tools, of which the following is a specification.

My invention consists, mainly, of an ice-pick in which a guard, handle, and blade are combined, substantially in the manner described hereinafter, the object of the implement being to chip from blocks of ice, without pulverizing the same, fragments approximating to uniformity in size.

In the accompanying drawings, Figure 1 is 15 a perspective view of my improved ice-pick; Fig. 2, a vertical section; and Fig. 3 a rear view, looking in the direction of the arrow, Fig. 2.

The improved ice-pick consists of three 20 main parts—namely, the guard A, preferably made of cast-iron, and the handle B and blade D, secured to the guard, the latter being composed of the bar a and pendent flange b, which, for economical reasons, I generally cast in one 25 piece with the bar. An opening, d, of the character best observed in Fig. 3, extends through this flange, which is strengthened at the edges by ribs c c, and the flange is preferably curved outward at and near its lower 30 edge, as shown in Figs. 1 and 2. The blade is secured to the front edge of the bar a, and has a number of sharp chipping-teeth, e—four in the present instance.

In using the implement it is grasped by the 35 handle and struck forcibly downward, so that the chipping-teeth will be brought into violent contact with the block x of ice at a dis-

tance from the edge of the block determined by the distance between the flange b of the guard and the blade D, fragments approximating to uniformity in size being thus chipped from the block without pulverizing the ice, and these fragments, or the greater portion of them, passing through the opening d of the guard, and being directed by the flange b onto a tray or into a bowl or other suitable receptacle.

The blade may have a single chipping-tooth; but, for obvious reasons, it is better to provide it with a number of teeth, as shown. 50 Simple prongs, moreover, may be substituted for the flange b of the guard, and the chipping of fragments from the block of ice may be effected without making an opening, d, in the flange. The opening may, for instance, 55 be in the bar a at the top of the space between the flange b and blade D.

I claim as my invention—

1. An ice-pick in which a guard, A, handle B, and blade D, provided with one or more chipping-teeth, are combined, substantially in the manner set forth.
2. The combination of the guard A, having an opening, d, and curved flange b, with the handle B and blade D, attached to the guard, substantially as set forth.

In testimony whereof I have signed my name to this specification in the presence of two subscribing witnesses.

HERMANN ALBRECHT.
